UNITED STATES PATENT OFFICE

2,568,718

VARIABLE INDUCTIVE COUPLING

Torrence H. Chambers, Washington, D. C.

Application April 28, 1945, Serial No. 590,856

2 Claims. (Cl. 178—44)

(Granted under the act of March 3, 1883, as
amended April 30, 1928; 370 O. G. 757)

1

This invention relates to radio frequency oscillators or signal generators and, more particularly, to a test signal generator especially designed to deliver any of three selected types of radio frequency output, viz., a fifty percent square-wave modulation or a series of rapidly attenuated R.-F. pulses or an unmodulated (CW). The principal use of the signal generator of the present invention is as a generator of synthetic interference signals for use in the training of personnel in the operation of ultra-high frequency radio equipment, particularly receivers, but oscillators or signal generators of this type also are useful in producing modulated or pulsed radio frequency voltages of predetermined magnitude for use in checking receiver equipment and similar work where frequencies of extreme accuracy are not required.

One object of the present invention is to provide a radio frequency oscillator or signal generator including a novel attenuator arrangement for controlling the output voltage.

Another object of this invention is to provide a radio frequency oscillator or signal generator of the foregoing character which is of compact, rugged construction and completely self-contained in a single, readily-portable carrying case.

Another object of the invention is the provision of a signal generator having output characteristics such that it can be used either in the laboratory or in the field as a source of variable radio frequency voltages, approximately calibrated, for checking the operation and overall performance of high frequency radio receivers.

A further object of the invention is the provision of a signal generator having output characteristics such that it can be used in the laboratory or in the field as a source of desired radio frequency test signals to simulate interference for purposes of training personnel in the operation of high frequency radio equipment.

A still further object of the invention is to provide a test signal generator of the type described which is of simple construction employing a minimum of components and without use of complicated or expensive circuits.

A feature of the invention is the arrangement and the novel method of attenuation for providing a variable R.-F. output having a selected degree of attenuation for subsequent use by a receiver or other high frequency device to be tested. In the illustrated embodiment, the attenuator includes a turnable or revolvable member which

2

comprises a coaxial line type swinging link member with terminal coupling loops at both end portions electrically connected together in a series circuit and angularly disposed for simultaneously adjustable electromagnetic coupling relationship with a pair of fixed coupling loops. One of the fixed loops just mentioned is part of a coaxial line output line from the tuned circuit of the R.-F. oscillator and the other fixed coupling loop is characterized in that it forms an externally disposed extension of the inner conductor of the attenuator output line at an intermediate portion thereof. Means are provided for adjusting the swinging link to vary the inductive coupling relationship simultaneously between the associated loops and the fixed coupling loops to control the output voltage of the attenuator system.

A further feature of the invention is the arrangement and the novel method of coupling into a coaxial line by use of a loop formed of a portion of the inner conductor which has been pulled out through a side opening in the outer conductor of said line.

Other objects, features and advantages of the invention will be apparent from the following detailed description of a preferred embodiment thereof taken in connection with the accompanying drawing, in which:

Fig. 1 shows in block schematic diagram form the several units included in a test signal generator arranged in accordance with the present invention;

Fig. 2 is a diagrammatic representation showing the mounting of the swingable coaxial link coupling whereby swinging movement thereof is attained about the coaxial line "per se" as an axis.

Referring more particularly to Fig. 1 the test signal generator comprises a multivibrator 10, a audio amplifier stage 11, a high frequency oscillator 12, an adjustable output attenuator 13 and a power supply source 14.

The multivibrator 10 comprises a twin-triode, heater-cathode type tube arranged in a conventional symmetrical multivibrator circuit consisting of a two stage resistance-capacity coupled vacuum tube amplifier in which the output of each stage is coupled to the input of the other stage. The coupling means for the multivibrator 10 includes a plurality of resistance-capacity combinations selectively coupled between the inputs and outputs of the stages to render the multivibrator 10 capable of operating to a plurality of selected frequencies.

The output of the multivibrator 10 is fed through a coupling capacitor to the control grid of a power amplifier tube. The power amplifier tube is of a pentode type having a cathode, a screen grid, a suppressor grid, a control grid, and a plate. The foregoing elements are connected in a conventional manner to operate the power amplifier tube as an audio amplifier 11 in a manner well understood by those skilled in the art.

The oscillator 12 comprises a high frequency vacuum tube oscillator which may be of the Hartley type and having a tunable oscillatory circuit which includes an inductance and a variable capacitor associated therewith. The frequency of the oscillator 12 is controlled over the entire frequency band by adjustment of the variable capacitor in accordance with an approximately calibrated frequency scale on the control panel (not shown).

In the construction of the signal generator, as has been previously stated above, it is intended that three types of output shall be delivered, viz., fifty percent square-wave modulated or a series of rapidly attenuated R.-F. pulses or an un-modulated CW. To this end, switching devices 40 and 41 are provided to permit selection of either square-wave modulation or pulse operation of the oscillator.

The output attenuator 13 comprises a coaxial line having at one end a loop 51 (which may be a single turn loop or a plurality of turns) this loop taking a small portion of the R. F. voltage developed across the oscillator tuned circuit and transferring it by inductive coupling to the end loop 52 of the swingable link coupling 53. The link coupling 53 is a substantially U-shaped coaxial line (see Fig. 2) having arms 54 and 55, the loop 52 terminating the end of arm 54 while at the end of arm 55 is a terminal loop 56 which transfers this energy by inductive coupling to a loop 57, the latter loop being part of the inner conductor of a coaxial line 58 and projecting outside thereof through an aperture 59 in the outer conductor of said line at an intermediate point thereof. In Fig. 2 there is shown diagrammatically the general arrangement of the attenuator 13 wherein the coaxial link coupling 53 is supported so as to be swingable about an intermediate portion of itself as an axis, by means of a sleeve 60, to simultaneously adjust and control the inductive coupling between the pairs of loops 51, 52 and 56, 57. Suitable gearing mechanism, such as gears 61 and 62, is provided operable by means of a knob 63 in conjunction with an approximately calibrated scale on the control panel to adjust the attenuator and consequently to control the supply of output R. F. energy from the oscillator 12 to the radio receiver under test (not shown) through suitable transmission lines (not shown) placed in series with the loop 57 and connected by means of suitable connections to the terminals of the coaxial line 58, the performance of this radio receiver in turn being observable in conventional manner on the screen of a cathode ray tube.

In accordance with the circuit arrangement of this invention as described above it will be seen that by means of the switches 40 and 41 the R. F. output of the signal generator may be amplitude-modulated or pulse-modulated. The attenuator 13 provides a variable R. F. output which is approximately calibrated. Power is supplied from a conventional type of power supply 14 to the test signal generator. The power supply 14 includes an input transformer energized by a source

of alternating current. The secondary winding of the transformer is connected to the plates of a duplex-diode. The rectified output is delivered from the filament of the duplex-diode in a manner well understood by those skilled in the art.

Important advantages of this improved attenuation and coupling system are that no sliding contacts are required at the attenuator device and that both input and output coupling members thereof are fixedly positioned mechanically.

From the above, it should be seen that the invention provides a novel arrangement and method of transferring and attenuating the flow of high frequency oscillatory energy from an input element to an output element one or both of which elements being a coaxial line and both of said elements being fixed at spaced locations from each other with the output element connected to draw off the attenuated energy and the input element excited with high frequency oscillatory energy. By adjusting the relative coupling between the input and the output elements and an intermediate energy transfer link circuit the high frequency energy transfer to the output element is controlled and attenuated to the desired extent.

Although only one embodiment of the present invention has been disclosed and described herein it is to be expressly understood that various changes and substitutions may be made therein without departing from the spirit of the invention as well understood by those skilled in the art. Reference, therefore, will be had to the appended claims for a definition of the limits of the invention.

The invention described herein may be manufactured and used by or for the Government of the United States of America for governmental purposes without the payment of any royalties thereon or therefor.

What is claimed is:

1. In combination with a generator for producing radio frequency energy, a voltage attenuator comprising input and output means, said input means comprising a coaxial line energized by said radio frequency energy and terminated in a fixed loop, said output means comprising a coaxial line having an aperture in the outer conductor thereof and a fixed loop comprising a portion of the inner conductor thereof extending outwardly through said aperture beyond said outer conductor, a coaxial line link member having the ends thereof terminated in loops, one loop of said link member inductively coupled to said input means loop and the other loop thereof inductively coupled to said output loop means and means for moving said link member to vary the inductive coupling between said inductively coupled loops.

2. In combination, an input means comprising a coaxial line terminated in a fixed loop, an output means comprising a coaxial line having inner and outer conductors and a fixed loop comprising a portion of the inner conductor extending through said outer conductor intermediate the ends of the latter, a coaxial line link member having the ends thereof terminated in loops, one loop of said link member inductively coupled to said input loop and the other loop thereof inductively coupled to said output loop, and means for rotating said link member to vary the inductive coupling between said inductively coupled loops.

TORRENCE H. CHAMBERS.
